his Attorneys.

UNITED STATES PATENT OFFICE.

ALLISON M. ROSCOE, OF DUBOIS, PENNSYLVANIA.

SAW-HANDLE.

SPECIFICATION forming part of Letters Patent No. 459,652, dated September 15, 1891.

Application filed January 14, 1891. Serial No. 377,705. (No model.)

To all whom it may concern:

Be it known that I, ALLISON M. ROSCOE, a citizen of the United States, residing at Du-
5 bois, in the county of Clearfield and State of
Pennsylvania, have invented certain new and
useful Improvements in Saw-Handles; and I
do hereby declare the following to be a full,
clear, and exact description of the invention,
such as will enable others skilled in the art to
10 which it appertains to make and use the same.

This invention relates to handles for cross-
cut saws, and aims to provide a handle that
can be readily attached to and detached from
the saw, and which when in position will grip
15 the saw firmly and prevent lateral buckling
thereof on the line of tension of the compress-
ing or gripping contrivance.

The improvement consists of the novel fea-
20 tures and the peculiar construction and com-
bination of the parts which will be hereinafter
more fully described and claimed, and
which are shown in the annexed drawings, in
which—

Figure 1 is a side view, parts being broken
25 away, of a handle embodying my invention,
showing its application to the end of a cross-
cut saw. Fig. 2 is a cross-section on the line
X X of Fig. 1, showing the upper portion of
30 the handle in full. Fig. 3 is a detached view
of the handle-socket. Fig. 4 is a detached
view of the revoluble disk. Fig. 5 is a de-
tached view of the saw-receiving socket.

The socket A, which is constructed to re-
ceive the handle C, the latter being held in
35 the socket by the screw or similar fastening
E, is provided with a threaded portion a, on
which screws the saw-socket D, the latter be-
ing internally threaded at d to correspond
40 with the threaded portion a of the socket A.
The slot d' in the socket D is just wide enough
to receive the saw F and prevent the latter
springing laterally when the saw is clamped
45 in the socket D. The disk G is secured to
the lower end of the socket A by the rivet or
stud g in such a manner as to turn freely and
independently thereof.

In assembling the parts the end of the saw
is thrust through the slot d' in the socket D,
and the socket A is inserted in the upper end
of the socket D and screwed down therein 50
until the disk G bears on the upper edge of
the saw with sufficient pressure to clamp the
saw in the slot d' between the lower closed
end of the said slot d' and the disk G. By
55 having the disk G revoluble the handle C can
turn while the said disk is held firmly in en-
gagement with the saw, thereby preventing
injury to the saw and facilitating the process
of clamping and unclamping the saw.

Having thus described my invention, what 60
I claim, and desire to secure by Letters Pat-
ent, is—

1. The combination, with the socket D, hav-
ing a slot through its sides to receive the saw
and having its upper end internally threaded, 65
of the socket A, having the exteriorly-threaded
portion a to screw into the socket D, and the
disk G interposed between the upper edge of
the saw and the lower end of the socket A
and having stud g, which enters the lower 70
end of the said socket A and forms a positive
connection between the said disk and the
aforesaid socket A, substantially as described.

2. The combination of the socket D, taper-
ing at its lower end and having its upper end 75
internally threaded and having slot d' in its
side, the saw having its end thrust through
the said slot d', the socket A, having exter-
nally-threaded portion a to screw into the
socket B, the handle C, fastened in socket A, 80
and the disk G placed against the end of
socket A and having stud g, which forms a
positive connection and journal between the
aforesaid socket A and the disk, substantially
as and for the purpose described. 85

In testimony whereof I affix my signature in
presence of two witnesses.

ALLISON M. ROSCOE.
